US00D804598S

(12) **United States Design Patent** (10) **Patent No.:** **US D804,598 S**
(45) **Date of Patent:** **** Dec. 5, 2017**

(54) **FLOOR AND BEAM BACK HANDSPRING TRAINING APPARATUS**

(71) Applicant: **Endless Mountains Gymnastics, LLC**, Wyalusing, PA (US)

(72) Inventor: **Damon B. Albert**, Wyalusing, PA (US)

(73) Assignee: **Endless Mountains Gymnastics, LLC**, Wyalusing, PA (US)

(**) Term: **15 Years**

(21) Appl. No.: **29/533,117**

(22) Filed: **Jul. 14, 2015**

Related U.S. Application Data

(62) Division of application No. 29/498,659, filed on Aug. 6, 2014, now Pat. No. Des. 740,902.

(57) **CLAIM**

The ornamental design for the floor and beam back hand-spring training apparatus, as shown and described.

DESCRIPTION

FIG. 1 is a front perspective view of the floor and beam back hand-spring training apparatus;

FIG. 2 is a rear perspective view of FIG. 1;

FIG. 3 is a left side view of FIG. 1;

FIG. 4 is a right side view of FIG. 1;

FIG. 5 is a back view of FIG. 1;

FIG. 6 is a front view of FIG. 1;

FIG. 7 is a top view of FIG. 1; and,

FIG. 8 is a bottom view of FIG. 1.

The broken lines in the drawings represent unclaimed subject matter and form no part of the claim.

1 Claim, 8 Drawing Sheets
